UNITED STATES PATENT OFFICE

ALBERT P. BROOKS, OF BOSTON, MASSACHUSETTS

ROTARY WASHING MACHINE

Application filed January 13, 1923, Serial No. 612,447. Renewed January 3, 1929.

This invention relates to a rotary washing machine adapted to operate upon a plurality of washings simultaneously, each kept separate from the others by means of individual containers.

The principal objects of the invention are to provide a rotary supporting mechanism for a number of these containers located in a washing vat; to provide the supporting mechanism in a compact and simple form and of such shape that the containers can be moved into it through one end and will not have to be fastened against motion in a radial direction; to provide the supporting means with anti-friction devices so that the containers can be loaded and unloaded easily; to provide racks at the ends of the device for use in directing the containers toward and from the machine; and to provide improvements in the containers themselves.

Reference is to be had to the accompanying drawings in which

Fig. 1 is a plan of a washing machine constructed in accordance with this invention with the cover of the vat removed;

Fig. 2 is a transverse sectional view on enlarged scale;

Fig. 3 is a plan of a rack or platform for loading or unloading;

Fig. 4 is a longitudinal sectional view on enlarged scale on the line 4—4 of Fig. 3 showing details thereof;

Fig. 5 is a transverse sectional view of one of the containers for the washings; and

Fig. 6 is a side view of the same.

The invention is shown in a form involving a vat 7 of general cylindrical form and of such length as may be desired. It is supported rigidly and provided with pipes 8 and 9 for introducing hot and cold water at will. Each end of the vat is provided with a door 10 in the form of a quadrant, preferably, through which the washings can be introduced or removed. Its lower side is located conveniently at the same level as the loading platform or rack 11 at one end, and a similar rack 15 at the other end.

Each of these racks consists of a frame made up in any desired way, and provided with a series of freely rotatable shafts

12 mounted on side pieces 13 and each having rollers 14 thereon. This rack for loading is located at one end of the vat and registers with a horizontal line drawn from the center of the vat, and the unloading platform 15 is located opposite it at the other end. I have not shown any means for rotating these rollers by power. The containers for the washings can be pushed in over the rollers by hand.

Extending centrally and longitudinally through the vat from end to end is a main shaft 20. This can be driven by power in any desired way, but I prefer to provide gearing for driving it a few revolutions in one direction, reversing, and then driving it in the opposite direction automatically, but I have not shown any gearing for that purpose herein.

On this shaft are provided opposite pairs of radiating arms 21, the arms of each pair being spaced longitudinally along the shaft from the arms of the next pair which are arranged at ninety degrees therefrom. The pairs of arms are arranged alternately. Each of these arms is formed of strong material of any desired kind, and at the end each one is provided with a transverse cross-piece 22 and preferably with angle irons 23 located under its edges.

On these arms 21 are located shafts 24 having anti-friction rollers 25, which, when the arm is horizontal, register with the two racks 11 and 15 at the ends.

The individual washings are intended to be arranged in sector shaped containers which are shown in Figs. 5 and 6 as being of wood, although metal containers can be used. Each of these is of quadrant form having two sides 30 at right angles to each other, and a curved front side 31 concentric with the center of the machine, so that they are three sided. The curved side has a door 32 adapted to be hinged to it near one end, and detachably connected at the other side by means of hooks 33 or the like. These three sides 30, 31 and 32 as well as the door 32 are all provided with a series of small perforations. The containers are completed by two ends 34 which preferably are not perforated.

The operation of the device is very simple.

The individual washings in the containers are placed on the roller platform at the left in Fig. 1. These are moved in the opening 10 at the end on the rollers 14 and 25, preferably by hand. Twelve containers are moved in, one after the other in a single line from the rack 11 and, as each is moved in, the others are forced along on their rollers until one section of the device is filled. Then the 5 shaft is rotated a quarter revolution, and the next section filled in the same way. If the machine is entirely filled in the size indicated in the drawings, there will be forty-eight washings. When located on the rollers 25 in the machine the containers are held 10 in position and prevented from being disconnected from the frame or dislodged therefrom by the overhanging ends of the bars 22 and the angle irons 23 at the ends of the arms. 15 They are supported on the arms 21 and come in to contact with the vertical arms corresponding therewith which alternate with them as stated. It will be understood that the angle irons 23 constitute tracks on which 20 the receptacles are supported and also prevent their being dislodged by centrifugal force in a radial direction, but they allow them to be moved along the vat and of course 25 guide them through it.

30 Power is then turned on, and the machine rotated preferably with an oscillating motion. Only a small amount of water is required in the bottom as the perforated forward upper sides of the several containers receive a small part of the water and raise it 35 with them a little as they rotate. The water pours into each container through the perforations therein and is turned therewith by the rotation of the shaft. The water has through 40 access to all of the closing before it passes out through the perforations opposite. It has been found in practice that a very thorough cleaning operation is provided by this means. The introduction of the water 45 in small streams against the clothing itself tends to loosen and dislodge the dirt from the articles in the container, and the water continuously passes back and forth through it as the shaft is turned in opposite directions.

50 The wash vibrates back and forth in the containers. After having been washed with a soapy warm water that can be drawn off rinsing water can be introduced either with or without stopping the operation of the 55 shaft and the rinsing operation can take place therefore immediately after the washing. Blueing can be introduced, of course if desired.

When the operation is completed, whether 60 the washing is all done in this one machine or not, the machine is stopped with one of the sets of arms 21 horizontal and the doors 10 at opposite ends opened. It is intended that there shall be a new set of washings on the 65 rack 11 ready to introduce and as they are in-

troduced at one end from the roller platform those that have been through the process are forced out at the other end one by one on the delivery roller rack 15. When enough have inserted to fill one longitudinal space the 70 shaft is rotated a quarter of a revolution and the process repeated until the containers having the washings that have been finished are all discharged and the machine is again 75 filled ready to have the process repeated.

This arrangement can be used for washing or rinsing or blueing, or all three combined, and it can be used for white or colored clothes, but it is not intended ordinarily to be used for both at the same time.

It has been found in practice that this machine can be designed to take care of a large number of individual washings at the same time, and on account of keeping each wash in its own container from the time it enters 80 the laundry until it is ready to be discharged the customers are much better satisfied, and the trouble involved in checking up the clothes is almost entirely eliminated. Furthermore there is no necessity of marking the 85 clothing in any way. The system which I have employed is to place in the container a tag 40 formed of brass or other metal and have a duplicate tag 40 which will indicate 90 the owner. This is all the checking or marking that is necessary. This tag is located 95 in a slot 41 in the inside surface of one of the ends of the container under the edge of the cover 32. This slot is undercut on its side so that the tag or check will be held therein 100 by the undercut edges and the cover. The tag or check can be inserted in a substantial radial direction when the cover is open. When the cover is closed the end of the slot is closed thereby and the tag or check cannot 105 come out, so that there is no danger of getting them mixed up.

After the clothing comes out of this machine preferably it is rough dried by means of centrifugal driers of well known type. 110 This permits of the handling of a very large number of washings in minimum time, and the performing of the washing operation with much more efficiency than has been the case heretofore.

Although I have illustrated and described only a single form of the invention I am aware of the fact that modifications can be made therein by any person skilled in the art without departing from the scope of the invention 115 as expressed in the claims.

Therefore I do not wish to be limited to all the details of construction herein shown and described, but what I do claim is:—

1. In a washing machine, the combination 125 with a vat for containing the washing water, a longitudinal shaft extending therethrough having radial arms, and a series of angle irons at the ends of said arms projecting outwardly therefrom tangentially and constitut- 130

ing with the arms and shaft a rotary frame, of a series of containers for the individual washings, each having two walls at an angle to each other equal to the angles between said arms, said containers each having a curved wall connecting them and arranged to detachably rest on the arms, the angle irons acting as tracks to guide the containers along them, whereby containers can be introduced at one end of the frame and forced along to load up the frame.

2. In an article of manufacture, a sector shaped container for clothing adapted to be mounted in a washing machine, comprising a receptacle having two flat sides at an angle to each other, and a third side of arcuate shape connecting their ends, said three sides being perforated to permit the passage of water, and two flat ends parallel with each other connecting said sides, one side having as a part of it a removable cover for the introduction and discharge of the contents, one of the ends being provided with an undercut slot extending in from the edge which the cover engages, for the reception of an indicator and adapted to be closed by the closing of the cover.

3. As an article of manufacture, a container for clothing adapted to be mounted in a washing machine, comprising a receptacle having sides and ends parallel with each other connecting said sides, one side having as a part of it a removable cover for the introduction and discharge of the contents, one of the ends being provided with an undercut slot extending in from the edge which the cover engages for the reception of an indicator and adapted to be closed by the closing of the cover.

40 In testimony whereof I have hereunto affixed my signature.

ALBERT P. BROOKS.
